UNITED STATES PATENT OFFICE.

FREDRICK E. GUBIN, OF RACINE, WISCONSIN.

RESERVE-SUPPLY TANK.

1,416,554.

Specification of Letters Patent. Patented May 16, 1922.

Application filed July 2, 1921. Serial No. 482,188.

To all whom it may concern:

Be it known that I, FREDRICK E. GUBIN, a citizen of the United States of America, and resident of Racine, Racine County, 5 State of Wisconsin, have invented certain new and useful Improvements in and Relating to Reserve-Supply Tanks, of which the following is a specification.

This invention relates to means for assuring a fuel reserve in the liquid fuel supply systems of motor vehicles; and the objects and nature of the invention will be readily understood by those skilled in the art in the light of the following explanation of 10 the accompanying drawings illustrating what I now believe to be the preferred mechanical expression or embodiment of my invention from among other forms, constructions and arrangements within the 15 spirit and scope thereof.

By reason of unpleasant experiences due to exhaustion of their fuel supply at locations far from gasoline supply stations, drivers of motor cars appreciate the desirability and advantages of motor car fuel supply systems that provide for small reserve supplies of fuel that can be drawn on when the progress of the motor car is halted by exhaustion of the main fuel supply.

30 An object of my invention is to provide a simple and efficient reserve fuel regulator by means of which a small reserve supply of fuel can be established in a motor car fuel tank, in readiness to be drawn on in case 35 of need by the manual manipulation of a device normally cutting off flow of fuel from said reserve to the carburetor.

With these and other objects in view, my invention consists in certain novel features 40 of construction and in combinations and arrangements more fully and particularly set forth and specified hereinafter.

Referring to the accompanying drawings:

Fig. 1 is a view partially in vertical section and partly in side elevation, showing a part of the lower portion of a liquid fuel tank of a motor vehicle having an embodiment of my invention applied thereto.

Fig. 2 shows a portion of the tank in vertical cross section, with the embodiment of my invention applied thereto and shown in part in vertical section.

Fig. 3 is a detail vertical longitudinal section of the device of my invention.

55 In the drawings, I show a part of the bot-

tom portion of the main gasoline or other main liquid fuel supply tank 1 of a motor vehicle such as a motor car, motor boat or the like. This tank has a vertical bottom opening or outlet formed by a vertical socket 60 or bore extending through a bushing or the like 2 fixed to the tank and fitting in a hole in the tank bottom, in the usual or any suitable manner.

Entrance to the tank for drawing off the 65 fuel, is established through this outlet, by means through which the fuel flows to the pipe or tube 3 leading to the carburetor. Such means embody a tubular casing or coupling 4 at its upper end forming a nipple or plug 5 fitted tightly in and extending through the bottom outlet of the tank and secured therein to form a liquid tight joint with the bushing 2 by screw threads or other securing means. This tubular casing depends from the tank bottom, and at its lower end is preferably exteriorly formed, at 6, to receive a wrench or other suitable tool by which the casing can be rotated for securing in and removing from the tank outlet 75 opening.

The casing is also preferably formed with a longitudinal screw threaded socket 7 opening through its lower extremity, for the attachment of any suitable depending trap 8, to which the carburetor feed pipe 3 is coupled in any suitable manner. The arrangement is such that the liquid fuel flows down from the tank through casing 4 into the trap 8. The fuel flows laterally from the trap, 90 at a point intermediate the depth thereof, into the carburetor feed pipe 3. The trap is preferably provided with a fuel cut off valve controlled by exterior accessible handle 9, by which the flow of fuel to the carburetor can be cut off, as is understood by those skilled in the art.

The upper end of the trap forms a threaded nipple 10 to screw into the socket 7, while the lower end of the trap is formed with a 100 drain opening normally closed by plug 11. The trap has a side outlet formed to permit coupling of the pipe 3 thereto, so that the fuel for pipe 3 is drawn from the upper part of the trap, permitting precipitation of 105 dirt and sediment in the trap. The trap is formed with a vertical liquid duct 12 extending through the nipple 10 to receive the fuel from casing 4 and discharge the same into the trap chamber, and this duct is con- 110

trolled by the plug valve operated by handle 9.

The casing 4 provides a main fuel supply duct 13 leading from the interior of the tank 1, to the socket 7, and also a reserve fuel or auxiliary supply duct 14 leading from the interior of said tank to the socket 7. The lower or outlet ends of ducts 13, 14, open through the top wall of socket 7, so that the lower ends of both said ducts are in free and unobstructed communication with the upper or inlet end of duct 12 when the trap is secured to the casing 4, as shown by Fig. 1.

The upper or inlet end of main fuel supply duct 13 is arranged in tank 1, a distance above the bottom of said tank, to establish a reserve fuel supply, while the upper or inlet end of reserve fuel duct 14 is flush or approximately level with the lowest portion of the fuel tank bottom so that the tank can be approximately drained through duct 14.

The main supply duct 13 is open and unobstructed throughout its length for the free flow of fuel to the trap, whereas the reserve fuel duct 14 is normally closed against fuel passage. The elevated inlet of the main supply duct 13 to provide the reserve fuel supply in the tank, is, in the example illustrated, established by an upstanding or vertical tubular extension 15 of the casing 4. The tube 15 is open at its upper end for inflow of fuel and the otherwise imperforate length of the tube above the upper end of the casing 4 determines the level of the reserve fuel supply. This tube 15 can be made in one piece with casing 4, or can be formed by securing a short length of straight tube to said casing. Usually, the length of tube 15 is such as to provide a reserve fuel supply of approximately one gallon more or less.

The ducts 13, 14, are usually separate and extend longitudinally through the casing 4. The duct 14 opens through the upper end of the casing 4 about flush with the tank floor, and this duct is traversed and normally closed by rotary plug valve 16 extending transversely through the casing 4 and duct 14 and provided with exterior operating handle 17. The plug of this valve 16 is formed with a transverse side recess or passage 18 located intermediate the length of the plug and adapted to be brought into alignment with the duct 14 to open the duct 14 to flow of fuel past the valve (see Fig. 3).

A supplemental cut off or valve 19 is also provided within the tank to cover and uncover the inlet end of duct 14 and prevent collection of sediment in the upper end of said duct as well as to clear sediment from the tank bottom at the duct inlet when said inlet is opened by movement of said valve.

In this instance, I show a reciprocating cap or disk valve 19 secured to the upper end of straight stem 20 and carried thereby. This

stem depends in the duct 14 and at its lower end is provided with an enlarged rounded head 21 held against the rotary valve 16 by coiled expansion spring 22 compressed between said head 21 and an annular shoulder 23 formed by the enlargement of the duct 14 to receive the spring.

The cap valve or closure 19 is arranged above the upper end of the casing 4 in alignment with the axis of duct 14, and said valve is of such size and form as to fit down on the upper end of said casing and close and cover the inlet end of said duct when said valve is at its limit of downward movement, and to permit free flow of fluid from the bottom of the tank into duct 14 when said valve is at its limit of upward movement. The spring 22 constantly acts to hold the head 21 against the surface of the rotary valve 16 and constantly tends to hold valve 19 in closed position or to return the same to closed position, and the rotary valve is so formed where engaged by head 21, that when the rotary valve is in position closing the duct 14, the reciprocating valve 19 will automatically assume its position covering and closing the inlet end of duct 14, and when rotary valve 16 is rotated to open the duct 14 (Fig. 3) the valve 19 will be automatically lifted to uncover the inlet end of duct 14, and when the rotary valve is rotated to close the duct 14, the valve 19 will automatically descend to cover and close said inlet end of the duct. The surface of the rotary valve acts as a cam in raising the spring pressed valve 19 and permitting descent thereof, through the medium of the valve stem 20 and its head 21. The surface of the passage or depression 18 in the rotary valve and the relatively elevated duct closing portion thereof are utilized for this purpose in co-operating with head 21.

If the motor car driver permits his supply of fuel to become exhausted to the liquid level of the inlet end of projecting tube 15, the motor will stop. On investigation, the driver will discover that his fuel is exhausted except for the supply held in reserve in the tank by the elevation of the main supply inlet 15. The driver will then swing the valve handle 17 down from the horizontal position (Fig. 1) to the vertical position (Fig. 3) thereby opening the duct 14, and elevating closure valve 19 to uncover the inlet in the tank bottom to duct 14.

The closure valve 19 not only prevents sediment from collecting in and closing the upper end of duct 14 above the rotary valve 16, but also forcibly clears sediment in the tank above the valve and opening, when the valve is forcibly elevated by the rotation of valve 16.

It will also be noted that the means for establishing the reserve supply in the main fuel tank and for controlling said reserve

supply, are all carried by the casing 4, and hence that no change is required in tank and pipe line constructions, and that my improvement can be easily applied to motor vehicles as now constructed, as well as to those now in use.

It is evident that various changes, modifications and variations might be resorted to without departing from the spirit and scope of my invention and hence I do not wish to limit myself to the exact disclosures hereof.

What I claim is:

1. An outlet casing for a liquid fuel tank providing a reserve fuel duct having a fuel inlet opening vertically into the tank at the bottom thereof to draw reserve fuel therefrom, movable means normally covering said vertical inlet against entrance of sediment from the tank, said means being constructed to raise sediment on the tank bottom over said inlet when said means is moved to uncover the inlet for entrance of reserve fuel, and manually actuated means controlling the operative position of said movable means to cover and uncover said vertical inlet.

2. A casing for coupling to a liquid fuel tank providing a normally-closed reserve fuel passage constructed and arranged to draw the reserve fuel from the tank, and spring-held manually controlled means for opening and closing said passage for the off flow of reserve fuel embodying an element, movable to and from normal operative position, and normally covering the inlet from the tank into said reserve passage to normally close said passage against entrance of sediment and the like from the tank.

3. A casing for coupling to a liquid fuel tank, said casing providing a normally-closed reserve fuel passage constructed and arranged to draw the reserve fuel from the tank, and means for opening and closing said passage for the off flow of reserve fuel involving means movable in the tank to cover and uncover the inlet of the passage in the tank and a manually operated cut-off valve controlling the position of said means in the tank and arranged exteriorly of the tank.

4. A liquid fuel tank for motor vehicles having an off take passage provided with an inlet in the tank elevated above the tank bottom to establish a reserve fuel supply, said tank having a normally-closed reserve fuel offtake with an inlet from the bottom of the tank interior, and manually-controlled means to close and open said reserve fuel offtake to flow of reserve fuel embodying a vertically movable cap in the tank and normally covering said inlet from the bottom of the tank.

5. An outlet casing for a liquid fuel tank providing a main fuel duct having an inlet

from the tank, and also providing a reserve fuel duct having a fuel inlet opening vertically into the tank at the bottom thereof, movable means normally covering said vertical reserve fuel inlet against entrance of sediment from the tank and constructed to displace sediment when moved to uncover said vertical inlet, and manually-operated rotary means controlling the operative position of said movable means to cover and uncover said vertical inlet, said rotary means being carried by and operative from the exterior of said casing.

6. A liquid fuel tank for motor vehicles having an offtake passage provided with an inlet in the tank elevated above the tank bottom to establish a reserve fuel supply, said tank having a normally-closed reserve fuel offtake with an inlet from the bottom of the tank interior, and manually-controlled means to close and open said reserve fuel offtake to flow of reserve fuel including a cut-off for said reserve fuel offtake and a member actuated by the cut-off to cover and uncover the inlet to said offtake.

7. A liquid fuel tank for motor vehicles having a fuel outlet to the carburetor elevated above the tank bottom to establish a reserve fuel supply, and an outlet to the carburetor from the tank bottom for flow of said reserve fuel, in combination with manually-controlled means for normally preventing flow of fuel through said outlet from the tank bottom and for capping said outlet to normally prevent entrance of liquid and sediment.

8. A liquid fuel tank for motor vehicles having a fuel outlet to the carburetor elevated above the tank bottom to establish a reserve fuel supply, and a vertical outlet to the carburetor from the tank bottom for flow of said reserve fuel, in combination with manually-controlled means for normally preventing flow of fuel through said outlet from the tank bottom embodying a movable member to normally cover said outlet and constructed to rise from the tank bottom to uncover said vertical outlet, and a manually operated cut off valve controlling the operative position of said movable member and having exterior accessible operating means.

9. A liquid fuel tank for motor vehicles having a fuel outlet to the carburetor elevated above the tank bottom to establish a reserve fuel supply, and an outlet to the carburetor from the tank bottom for flow of said reserve fuel, in combination with manually-controlled means for normally preventing flow of fuel through said outlet from the tank bottom embodying a member movable vertically in the tank to cover and uncover said outlet and having lifting means depending through said outlet and controlling the vertical position of said member, and manually-operated means exteriorly ac-

90

100

110

120

cessible and arranged below said outlet and operatively-cooperating with said lifting means to control the vertical position thereof.

10. A liquid fuel tank for motor vehicles having a fuel outlet to the carburetor elevated above the tank bottom to establish a reserve fuel supply, and an outlet to the carburetor from the tank bottom for flow of said reserve fuel, in combination with manually-controlled means for normally preventing flow of fuel through said outlet from the tank bottom embodying a vertically-movable spring-held member to cover and uncover said outlet and a rotary device controlling said member and actuating the same against the pressure of its spring.

11. A fuel-discharge casing for securing in a motor vehicle liquid fuel tank, the outer end of said casing formed to receive and discharge the fuel into a trap adapted to have the carburetor supply tubing coupled thereto, said casing having a main fuel supply duct discharging into said trap and having an elevated inlet to draw fuel from the tank 25 at a level a distance above the tank bottom,

said casing also having a reserve fuel inlet through which fuel from the tank bottom can be discharged to said trap, and manually-controlled means for normally preventing flow of fuel through said reserve fuel inlet including a rotary plug valve and a vertically-reciprocating valve to cover and uncover said inlet and having a depending stem, and a spring yieldingly holding said reciprocating valve in closing position and 35 said stem against said plug valve.

12. A fuel discharge casing for securing in a reserve fuel tank, having a main supply offtake and a reserve fuel offtake with a vertical inlet in the tank bottom, and manually controlled means for normally covering said inlet against passage of sediment and for closing said offtake against flow of reserve fuel, including a rotary cut off valve having an exposed handle, and a spring-held vertically movable closure for and above said inlet and having a depending actuating stem in operative relation to said valve to control the vertical position of said closure.

FREDRICK E. GUBIN.
